UNITED STATES PATENT OFFICE.

BUTLER P. CRITTENDEN, OF WATERTOWN, AND ALVIN C. KILLINGER, OF EVERETT, MASSACHUSETTS, ASSIGNORS TO BEACON OIL COMPANY, OF BOSTON, MASSACHUSETTS, A CORPORATION OF MASSACHUSETTS.

EXCAVATING DEVICE.

Application filed October 1, 1926. Serial No. 138,878.

This invention relates to excavating devices for removing masses from containers and other uses, the excavating devices being adapted to operate in respect to impacted 5 or hard material to bore a comparatively large hole, through and into which the material surrounding the hole may be broken down by hand operations.

Important uses for which devices corresponding to the invention are particularly suitable are for cleaning the hard coke or accumulated carbon and other analogous residues out of the soaking drums of petroleum cracking apparatus; for breaking 10 out filter beds and tank residues; and in general for excavating materials from large containers. In a familiar type of cracking apparatus the soaking drum, for example, is a structure made of heavy boiler plate, which 15 may be as much as six feet in diameter and forty feet high, having pipe connections for through pass of very hot oil. In the course of operation for six or seven days more or less the coke deposit from the oil treated is 20 sufficient to substantially close off flow, upon which the usual practice is then to drain out any contained liquid through a bottom opening, to remove the bottom cover from the soaking vessel, and to dig the carbon out 25 by such hand-tool methods as may be. Since the temperature is high and there are residual gases, and especially since the carbon 30 deposit in the drums is often such as to oxidize at the temperature at which it has to be cleaned out whenever both the bottom and top openings of the soaking drum are 35 open, the operation of cleaning out the coke is both difficult and dangerous. The old way was to use a stopping drill operated 40 from and through the bottom opening of the drum. The nature of the coke deposit varies greatly; sometimes it is glass hard, at other times it is friable; but in any case, 45 the excavating operation was an arduous, disagreeable and expensive undertaking.

The best technique known to us for removing the deposit comprises boring a comparatively large hole in the deposit from bottom to top, then breaking through the annular, substantially cylindrical remainder, and breaking this down and out through the central hole.

This invention has for one of its objects to provide a power-operated device capable

of boring such a hole, operating in an improved way to perform the most unpleasant and dangerous parts of the task of excavating impacted contained masses. Other objects of the invention are to provide excavating machinery for the purpose indicated 60 and other purposes capable of being assembled and taken apart, and of being transported from one place to another.

In the drawings:

Fig. 1 is a sectional view of the device in 65 operating position in a soaking drum;

Fig. 2 is an enlarged section on the line 2—2 of Fig. 1;

Fig. 3 is a section on the line 3—3 of 70 Fig. 1;

Fig. 4 is a section on the line 4—4 of Fig. 1; and

Fig. 5 is a plan in section on line 5—5 of Fig. 1.

The device may comprise a borer having 75 an extensible driving shaft 1, and a thrust bearing 9, 11 exterior to the container, the shaft being interposed between said bearings and material in the container; having a boring head 2 at one end of said shaft, driving 80 and axially propelling means 3 for imparting to the shaft rotary and axial motion, respectively; and a shield 4 above the driving mechanism protecting the mechanism against 85 the excavated material.

Referring first to the means for imparting motion to the shaft 1; for this it is preferred to employ a driving wheel 5 having a lower plane bearing surface and splined to the shaft 1 by a key 6 on the 90 driving wheel free in a keyway 7 in the shaft. The wheel 5 may be a belt, gear or worm wheel driven suitably; as shown and preferred the wheel 5 is a worm wheel driven by a worm 8 which, in turn, may be driven in any suitable manner. It is convenient to drive the worm by a powerful portable reversing motor, not shown, which may be taken from place to place about the plant as needed. The device 100 as a whole may be mounted upon any suitably solid base, such as the mass of concrete shown at 9, adapted to resist the thrusts due to gravity and operation of the boring head; base 9 has a central aperture 105 beneath and through which the shaft 1 may extend into a suitable pit, and around which an annular thrust bearing surface

11 may be a part of the base 9; the annular bearing 11 as illustrated comprises a ball raceway in a metal ring attached to the base 9.

5 A nut 12 having an upper wide bearing surface and in threaded engagement with a threaded part 21 of shaft 1, is provided between the base 9 and the wheel 5 and may have on its lower portion a ring bearing shown as a ball raceway 13 opposite the raceway 11 in the base. Between these raceways are arranged balls 14 or any other suitable anti-friction device. The bearing between the wheel 5 and the nut 12 is not 10 so free a bearing as that between the nut 12 and the anti-friction devices such as 11 and 14, so that nut 12 and wheel 5 tend to turn in unison. But when the nut 12 is restrained from rotation, revolution of the 15 shaft 1 results in moving shaft 1 and its attachments axially by screw motion of the part 21 in nut 12. Any suitable means may be provided for braking the nut 12, for example a brake band 16 in a peripheral 20 groove 15 in the nut 12, band 16 being anchored at one end 17 in any suitable manner and connected at its other end 18 to a tensioning device, shown as a lever 19 fulcrumed at 20 to a suitable projection on 25 the base 9. The base and actuating mechanism may be enclosed in any suitable casting, not shown. The shaft 1, wheel 5, worm 8, nut 12, and brakes 16, 17, 19, are not too heavy severally to prevent each from being 30 carried from place to place to be re-assembled where the device may be needed.

Each section of shaft 1 is provided at 35 its ends with any suitable means for attachment to the next section, shown as a flange 22 which may be attached to the next adjacent section by bolts 23 in suitable holes. One end of each section may be provided with a central boss 24 adapted to fit in a 40 central recess 25 in the end of the next adjacent section. Only one intermediate section 26 is shown but it is to be understood that as many intermediate sections as are needed may be inserted in the device according to the height or distance desired 45 to be reached by the boring head 2.

The lower shaft section 21 has provided at its upper portion a flange 27 slightly larger than the flanges 22 conical at its periphery for connection with the rotary shield 4, which may be fastened on it suitably, as by bolts or rivets at 28.

Means are provided for holding at attained height one of the upper shaft sections such as section 26, when it is desired 50 to insert or take out a section, the lower section 21 of the shaft 1 being retracted by reversing the motion of wheel 5 for the insertion of an extending section. Such means may comprise a pair of levers 29 which may be pivoted at 30 to the lower

end of the soaking drum or vessel 46 to be cleaned, and if desired, lock under a hooked lug 29^a on the bottom flange of the drum or vessel 46, Fig. 4. Levers 29 are provided with intermediate arcuate portions 31 70 adapted to engage the shaft in one position of the levers, which are locked together to engage the portions 31 with the shaft 26, by a swing bolt 32 and nut 35 pivoted to one of the levers at 33 and fitting a forked 75 end 34 of the other lever. When not in use levers 29 are swung outward out of the way.

The boring head 2 may carry any effective boring tools, for example, a central bit 37 followed by a reaming shank 38; this 80 shank may have longitudinal channels 38' spaced equidistantly to accommodate folding cutters 41 pivoted at 40 between bored lugs on the upper face 42 of a collar 39 integral with reaming shank 38. Cutters 41 85 in their extended position rest against the upper surface 42 of collar 39. The cutters 41 are preferably T-shaped in cross-section, except at the butts bored for pivots 40, Fig. 2, and may be milled through at the upper 90 edges of their central rib to provide a plurality of substantial cutting teeth 43. The base portion 44 of the cutters 41 is relatively heavy, and one or both of the corners 45 is a sharp cutting edge, so that when the 95 cutters are folded as shown at dotted lines on Fig. 1, these sharp corners 45 constitute conical reaming cutters to bore a hole relatively smaller than the hole cut by the cutting edges 43 when the cutters are in the 100 full line position, Fig. 1. In this folded position, the central ribs of the cutters respectively are housed in the corresponding channels 38' of the reaming shank 38.

The device is shown in Fig. 1 in position 105 for boring a hole vertically upwardly through the contents of soaking drum 46, which may as usual be supported well above ground, as by lugs 47 resting on a strong frame including I beams 48. The drum 110 may be provided with suitable heat insulation 49. Oil is ordinarily introduced near the bottom of the drum through inlet pipes 50 and carried away near the top through pipes 51. The usual vapor outlet 52 and 115 draining pipe 53 and valve 54 may be provided. When it is desired to clean the drum, after the liquids are drained out, and the bottom cap, not shown, has been removed, the boring head and section 36 of shaft 1 is attached to section 21, and the cutters 41 are folded up against the reamer 38 and tied with a piece of wire, which may be cut after entrance. Shaft 1 is now driven, and the brake on nut 12 set up, 120 whereupon the bit 37 starts a central hole in the coke. The released cutters soon work themselves out into the position shown in full lines on Fig. 1. In that position they 125 may bore a hole of the order of four feet 130

or less to fifty inches or more in diameter. On starting, the coke in the bottom neck of the drum 46 may be broken out manually. On completion of the bore hole to the top 5 the remaining annulus of carbon residue may be broken out manually with bar, pick or shovel, the detritus passing down through the central hole. During boring, the operator may maintain the brake 16 tight enough to advance the cutter with such 10 force as is measured by the brake friction. From time to time, the detent levers 29 are closed, the motor reversed to back off the screw section 21, and a section 26 is inserted. 15

It will be observed that the nut 12 and the threaded section of the boring shaft comprise a type of lifting jack operated by the rotative energy by which the boring shaft 1 is driven, but we are not to be understood to limit our invention to any particular type of lifting jack since it is obvious to those skilled in the art that some other form of lifting jack (for example, another kind of screw or a fluid pressure jack thrusting coaxially with the shaft at its under end) might be substituted without involving change of operative effect except to forego some of the advantages of simplicity of construction and control of the preferred form above explained. Likewise, it will be understood that the described means for rotating the boring shaft 1 and for extending the shaft 1 from time to time are not the sole means corresponding to the invention, although preferred instances and recommended forms; and that the rotary cutter shown and described in a preferred instance only of such cutters for usual materials; whereas other forms of cutter might be substituted with benefit for different states of material, all without departing from our invention. 40

We claim:

45 1. Apparatus for excavating the contents of containers having in combination a thrust bearing fixedly mounted on the axis of an opening into the container, an axially movable shaft and propelling means therefor reacting against said thrust bearing, a boring head on said shaft, and means for rotating and for axially propelling said shaft as a consequence of its rotation, means for varying the propulsion thrust, and means permitting said shaft to be interposed and removed from interposition between said thrust bearing and said container. 50

55 2. Apparatus for excavating the contents of containers having in combination a thrust bearing fixedly mounted on the axis of an opening into the container, an axially movable shaft and propelling means therefor reacting against said thrust bearing, a boring head adapted effectively to expand radially to bore a larger hole after entrance into the

material to be excavated on said shaft, and means for rotating and for axially propelling said shaft as a consequence of its rotation, and means for manually varying the propulsion thrust. 70

3. Excavator for solids held in a container having therein, in combination, a thrust bearing in fixed relation to said container, a boring shaft, a boring head on said shaft, means for rotating said shaft in respect to 75 said bearing and means for causing said shaft to thrust axially in respect to said bearing, said shaft being extensible in respect to its length between boring head, and axial thrust causing means, said thrust causing means having a friction element controllable to vary the force of thrust exerted. 80

4. In an excavator for solids held in containers, in combination, a boring shaft, a boring head on said shaft having a bit rigid and coaxial with said shaft, cutters normally free for radial movement in respect to said bit and the axis of said shaft, means on said boring head for limiting the outward movement of said cutters, and means for rotating and axially thrusting upon said shaft. 90

5. In an excavator for solids held in containers, in combination, a boring shaft, a boring head on said shaft having a longitudinally recessed bit rigid and coaxial with 95 said shaft, cutters normally free for radial movement in respect to said bit and the axis of said shaft, means on said boring head for limiting the outward movement of said cutters, said cutters having cutting edges 100 severally adapted to be housed in said longitudinal recesses at one limit of their motion, and means for rotating and axially thrusting upon said shaft. 105

6. In a boring excavator for solids, a boring head having a bit adapted for rigid coaxial mounting on a boring shaft, said boring head comprising a plurality of cutters having effective cutting edges on at least two faces, said bit being recessed, said cutters being mounted for motion in radial planes of said bit between limits, a cutting edge of each cutter being adapted to be housed in each of said recesses in one position of the cutters, whereby other of said cutting edges 110 are then effective to ream a hole of one diameter, the parts in another position being adapted to bore a larger hole. 115

7. In an excavator for solids held in a container in combination with a thrust bearing fixed in relation to the container, a sectional boring shaft adapted to be separated and assembled, a boring head on the shaft, means permitting said shaft to be interposed and removed from interposition between said thrust bearing and said container, a drive mechanism for rotating the shaft adapted to be separated from and assembled with the shaft and thrust bearing, a screw jack mechanism for thrusting on the shaft having 120 125 130

one screw element on a section of said shaft and another screw element adapted to be interposed between said shaft and thrust bearing, and means for restraining free rotation of said interposed screw element in respect to said thrust bearing.

8. An excavating device for boring a long hole of large diameter in an upward direction comprising a sectional shaft mounted 10 for axial movement, a boring head on the

shaft, means in engagement with the bottom section of the shaft for imparting motion thereto, and means adapted to grip the section next to the bottom, whereby the bottom section may be retracted and an intermediate section inserted. 15
